UNITED STATES PATENT OFFICE.

RUFUS W. BLAKE, OF DERBY, CONNECTICUT, ASSIGNOR TO THE STERLING COMPANY, OF SAME PLACE.

PEDAL ATTACHMENT FOR PIANOS.

SPECIFICATION forming part of Letters Patent No. 445,035, dated January 20, 1891.

Application filed September 29, 1890. Serial No. 366,525. (No model.)

To all whom it may concern:

Be it known that I, RUFUS W. BLAKE, of Derby, in the county of New Haven and State of Connecticut, have invented a new Improvement in Pianissimo-Pedal Attachment for Pianos; and I do hereby declare the following, when taken in connection with accompanying drawings and the letters of reference marked thereon, to be a full, clear, and exact description of the same, and which said drawings constitute part of this specification, and represent, in—

Figure 1, a side view of the tail of one key and its action, showing the key-board in transverse section with end view of the bar E and side view of the pianissimo-pedal and its connection with said bar; Fig. 2, a rear view of the key-board and a portion of the keys, showing the bar E as hung thereon; Fig. 3, a plan view of the pedals; Fig. 4, a front view of the pedals, showing the connecting-levers.

This invention relates to an improvement in pianos, it having for its object to produce through the pedals a pianissimo effect and so that it may be combined with the soft pedal to produce an extreme effect of this character when desired; and the invention consists in the construction as hereinafter described, and particularly recited in the claim.

A represents the rear portion of the key-board of a piano, and B the tails of the keys. The action above the keys is of common construction. C represents the hammer, and D the tracker, by which the key communicates with the action. The construction of the action is too well known to require particular description. Longitudinally on the key-board a bar E is arranged so as to stand beneath the tails of the keys, as seen in Figs. 1 and 2. This bar is hung to the key-board by links F, which permit the bar to rise and fall and yet maintain a constant parallelism with the key-board and tails of the keys, and so that in rising it will strike the tails of all the keys and cause them to rise accordingly, or as it drops it will fall below the normal position of the keys and leave them free, as represented in Figs. 1 and 2.

In Figs. 3 and 4, G represents the usual soft-pedal and H the usual loud-pedal. Between

these pedals a third pedal I is arranged, hung in the usual manner, and at its rear end a pedal-rod J extends up and so as to bear upon the under side of the bar E, as clearly seen in Figs. 1 and 2, and so that as the pedal is depressed, as indicated in broken lines, Fig. 1, it will, through the connection of the rod J, cause the bar E to rise accordingly, as also indicated in broken lines. In such rising of the bar E under the pressure upon the pedal the bar strikes the under sides of the tails of the keys and raises them accordingly, as also indicated in broken lines, Fig. 1. This rising of the keys operates upon the action to take the hammer to a position nearer to the wires, yet leaves the hammer still under the control of the action to receive the blow, as indicated in broken lines, Fig. 1. This rising of the tails of the keys reduces the movement of the key accordingly and the force upon the hammer, so that the hammers under the force of the keys receive but short strokes, resulting in a corresponding slight force of blow, and so long as the bar E is held in this up position the keys and the action will remain in that same position, so that the said slight strokes will continue and a pianissimo effect will be the result.

The pedal I is independent of the soft-pedal G, so that the effect of the soft-pedal may be produced without the effect of the third or pianissimo pedal I. To produce an extremely soft effect, I provide a coupling of the pianissimo and soft pedals, which is best done as represented in Figs. 3 and 4. K represents a lever hung transversely above the pedal I and connected to the pedal by a rod L, so that the depression of the pedal I will correspondingly depress the lever K, as represented in broken lines, Fig. 4.

M represents the soft-pedal lever connected to the soft-pedal by a rod N, as usual. The lever M extends to a position beneath the lever K and so that when the pedal I is depressed it will also depress the lever M, and consequently apply the soft-pedal; but this leaves the soft-pedal independent of the pedal I, because in the depression of the pedal G the lever M is depressed independent of the lever K, but the depression of the pedal I will correspondingly depress the lever M.

The pianissimo-action of the pedal I is generally desirable only for extreme effects and in addition to the soft-pedal. Hence the two pedals are combined, so that a single pressure upon the pianissimo-pedal I may apply the effect of the soft-pedal in addition to its own pianissimo effect.

10 The lever K may be omitted, and so as to leave the two pedals to be operated with entire independence; but I prefer to employ the lever K, as the pedal I is seldom required, except as an addition to the operation of the soft-pedal.

I claim—

15 The combination of the parallel bar E, ar-

ranged beneath the tails of the keys and so as to move freely up and down to correspondingly raise or liberate the keys, the pedals G and I, in connection, respectively, with the lever M and the bar E, a lever K, hung to the 20 pedal I and so as to bear upon the said lever M under the depression of the said pedal I, substantially as described.

In testimony whereof I have signed this specification in the presence of two subscribers. 25

RUFUS W. BLAKE.
